Patented December 20, 1904.

UNITED STATES PATENT OFFICE.

FERDINAND STRAUSS, OF YONKERS, NEW YORK.

DESIGN FOR A HARMONICA.

SPECIFICATION forming part of Design No. 37,266, dated December 20, 1904.

Application filed November 8, 1904. Serial No. 231,956. Term of patent 7 years.

To all whom it may concern:

Be it known that I, FERDINAND STRAUSS, a citizen of the United States, residing at Yonkers, Westchester county, State of New York, have invented a new, original, and ornamental Design for Harmonicas, reference being had to the accompanying drawings, in which—

Figure 1 is a perspective view of a harmonica, showing my new design; and Fig. 2 is a front view thereof.

What I claim is—
The ornamental design for a harmonica, substantially as herein shown.

FERDINAND STRAUSS.
